Geo. S. Prindle, his Atty.

UNITED STATES PATENT OFFICE.

JOHN C. COPPER, OF PHILADELPHIA, PENNSYLVANIA.

DESIGN FOR UPHOLSTERY-TRIMMING.

SPECIFICATION forming part of Design No. 13,843, dated April 3, 1883.

Application filed February 23, 1883. Term of patent 3½ years.

To all whom it may concern:

Be it known that I JOHN C. COPPER, of Philadelphia, in the county of Philadelphia, and in the State of Pennsylvania, have invented certain new and useful Improvements in Design for Upholstery-Trimming; and I do hereby declare that the following is a full, clear, and exact description thereof, reference being had to the accompanying drawing, making a part of this specification, in which is shown in perspective a fringe having incorporated therein a block that illustrates my design.

My design consists of a fringe-block, A, which preferably has a tapering form, and has its entire periphery composed of diamond-shaped facets *a*, that are arranged in rows, each row breaking joints with the adjacent rows.

Said facets are concave vertically, and decrease in size as the diameter of the block lessens. The block A is covered with silk or other suitable material, or said covering may be entirely of one color.

Having thus fully set forth the nature of my invention, what I claim as new is—

A design for a fringe-block, substantially as shown and described.

In testimony that I claim the foregoing I have hereunto set my hand this 24th day of January, 1883.

JOHN C. COPPER.

Witnesses:

RICHD. C. WINSHIP,
J. M. HAZEL.
